LOW PRESSURE FUEL AIR INJECTION AND IGNITION SYSTEM

Stehman W. Leonard, Martinsburg, W. Va.

Application October 4, 1938, Serial No. 233,268

3 Claims. (Cl. 123—75)

The present invention relates to fuel air injection and ignition system for internal combustion engines and has for its primary object to provide a low pressure fuel air chamber mounted on the engine cylinder adjacent the high pressure chamber of an internal combustion engine, the low pressure and high pressure chambers having communication through mechanically operated or other suitable type valves and adapted to be moved in an open position slightly in advance of the completion of the compression stroke of the piston of the engine to admit the highly compressed air in the combustion chamber into the low pressure chamber to ignite the fuel therein for combustion purposes.

An important object of the present invention is to provide a low pressure fuel air injection and ignition system of this character designed primarily to eliminate the complicated fuel pump injectors and metering devices as at present employed in Diesel type engines whereby to improve the engine mechanically as well as to reduce the cost of manufacture thereof.

Other objects and advantages will become apparent from the following detailed description when viewed together with the accompanying drawings forming part hereof, wherein like numerals refer to like parts throughout and in which

Figure 1 is a transverse sectional view through an internal combustion engine illustrating a practical application of the invention.

Figure 2 is a fragmentary longitudinal sectional view.

Figure 3 is a top plan view.

Figure 4 is a side elevational view of the engine head.

Figure 5 is a transverse sectional view of a four-cycle engine embodying the present invention, and

Figure 6 is a fragmentary side elevational view of the engine head for the four cycle engine.

Referring now to the drawings in detail wherein for the purpose of illustration I have disclosed a preferred embodiment of the invention the numeral 5 designates an internal combustion engine generally which includes one or more cylinders 6 having a piston 7 operable therein, the upper portion of the cylinder constituting the high pressure or combustion chamber as at 8.

Secured to the top of the engine is a head 9 having a low pressure chamber 10 formed therein adjacent its bottom portion and communicating with the high pressure chamber 8 by means of an opening 11 which forms a valve seat and with which is associated a poppet type valve 12. The valve 12 extends upwardly through the top of the head and is actuated by the usual type

of rocker arm 13 pivotally mounted on a bracket 14 secured to the top of the head and operatively engaged by a push rod 15 extending vertically at one side of the engine for operation by a conventional type of cam shaft (not shown).

The head 9 is also provided with a fuel air intake port 16 communicating with a manifold 17 secured to one side of the head and with which a fuel air feed pipe 18 communicates.

10 The port 16 communicates with the lower pressure chamber 10 by means of an opening 19 which forms a valve seat and with which a poppet type valve 20 is operatively associated and which also extends through the top of the engine head and is likewise operated by an individual rocker arm and push rod of the type herefore described.

20 Air intake and discharge ports 21 and 22 are formed in the sides of the engine for admitting air into the cylinder 6 upon the completion of the down stroke of the piston 7 in a manner well known in the art.

25 The invention is adapted for use upon either two-cycle engines, as illustrated in Figures 1 to 4 inclusive of the drawings, or upon four-cycle engines as illustrated in Figures 5 and 6 of the drawings, the cycle of operation for the four-cycle Diesel type engine being as follows:

On the intake stroke of the piston, air is 30 drawn into the cylinder through the intake valve 27 cooperating with valve seat 28 from which the passage 29 leads through the head to the air intake pipe 30 which communicates with the atmosphere (or to a supercharger). The exhaust 35 is accomplished through the valve 12 cooperating with the valve seat 11 communicating with the low compression chamber 10, the latter being also provided with the exhaust valve 31 cooperating with valve seat 32 controlling communication to the exhaust pipe 33 through the passage 34.

As the piston 7 moves downwardly on the intake stroke the valve 27 opens admitting pure air to the engine either under pressure (or at atmospheric pressure), valves 12, 20 and 31 being closed on this stroke. As the piston 7 starts upwardly on the compression stroke the valve 27 also closes thereby causing a compression of air in the chamber 8 to 16 to 1 plus ratio (so as to maintain the 16 to 1 ratio when valve 12 opens). A few degrees before top center is reached valve 12 opens admitting highly compressed hot air into the low compression chamber 10, valves 20, 28 and 31 being closed at this time. Ignition 55 takes place, forcing piston 7 downwardly and as the piston starts upwardly on the exhaust stroke the exhaust valve 31 opens (valves 27 and 20 being closed at this time) and the burnt gases are forced out of the chamber 8 through valve 12 into chamber 10 and out through exhaust valve

31 into exhaust passage 34 and exhaust pipe 33, thereby clearing both chambers of burnt gases, and as the piston starts downwardly again on the intake stroke the valve 27 opens admitting pure air to the cylinder. At this time the valves 12 and 31 are closed and valve 20 is open, admitting fuel-air mixture under pressure from the manifold 17 through the passage 16 in the motor head to the low pressure chamber 10.

At this point let it be understood that by keeping the intake valve 27 closed and the valve 12 open during a portion of the intake stroke, that a partial vacuum is created in chambers 8 and 10 (at this time valves 20 and 31 being held closed) whereupon valve 12 closes and valve 27 opens so that air is admitted into the compression chamber before starting the compression stroke. As the piston 7 moves upwardly compressing air in the compression chamber, the valve 20 opens and due to partial vacuum in chamber 10, little or no air pressure is required to force the fuel-air mixture into the chamber 10 from the passage 16. By reason of this construction the use of an air compressor is not necessary and permits the use of an ordinary type of gasoline engine carburetor where gasoline is used as the fuel. At present gas engine compression ratios are not practical above 7 to 1 due to pre-ignition of fuel and gasoline as a fuel is not practical for compression ignition engines, due to the fact that it carries insufficient lubricating qualities for the present injection equipment and accordingly, the present invention makes it possible to use the gasoline for fuel and to employ conventional types of gasoline carburetors at 35 compression ratios of compression ignition engines.

In the two cycle type engine, ordinarily employing no valves, but intaking and exhausting through the ports 21 and 22, on the intake stroke or while the piston is at the bottom of the cylinder the intake port 21 is open and air is admitted into the cylinder at atmospheric pressure or may be boosted by supercharger if desired. When the piston approaches within a few degrees of top center the air is compressed to approximately 400 pounds per square inch which causes an increase in the temperature of the air to approximately 1,000 degrees F.

While the piston was at the bottom of the cylinder and the air being admitted thereto the intake valve from the fuel air manifold opens and admits fuel air mixture into the low pressure chamber while the exhaust valve between the chambers is closed. As the piston reaches the top of its stroke the exhaust valve from the low pressure chamber opens admitting the heated air from the combustion chamber into the low pressure chamber causing ignition of the gases and producing the power stroke as above explained. The exhaust port 22 is uncovered upon the down stroke of the piston as well as the intake port 21, the incoming air forcing out the exhaust gases as completing the two cycles of the two cycle engine.

It is believed the details of construction and manner of operation of the device will be readily understood from the foregoing without further detailed explanation.

What is claimed is:

1. In an internal combustion engine, a cylinder having a combustion chamber and an air

intake port for admitting air at atmospheric pressure to the chamber, a piston working in the cylinder for compressing the air in the chamber to a high pressure, a low pressure chamber above the cylinder, a feed chamber above the low-pressure chamber having a feed chamber and line connected thereto for supplying a combustible mixture at low pressure to the low pressure chamber, said low-pressure chamber being relatively shallow and of a diameter substantially equal to that of the cylinder and adapted for preheating and vaporizing fuel admitted thereto, a valve between the low pressure chamber and the feed chamber and a valve 15 between the combustion chamber and the low pressure chamber, said valves arranged for opposite opening and closing movement and said last named valve being adapted to provide communication between the combustion and low-pressure chambers at the approach of the peak of the compression stroke of the piston for utilizing the highly compressed air in the combustion chamber to ignite the fuel-air in the low pressure chamber.

2. In an internal combustion engine, a cylinder having air intake and discharge ports, a piston working in the cylinder, the upper end of the cylinder constituting a combustion chamber, a head closing the top of the cylinder, a low pressure fuel-air chamber in the head said low-pressure chamber being relatively shallow and of a diameter substantially equal to that of the cylinder and adapted for preheating and vaporizing fuel admitted thereto, the bottom of the head forming a bottom wall for said low pressure chamber and the top wall of the cylinder, a valve in said wall controlling communication between the chamber and cylinder, a fuel intake manifold in the head above the low pressure chamber and a valve controlling communication between the manifold and low pressure chamber and arranged for opening and closing movement opposite to said first named valve whereby to admit and retain fuel under low pressure in the low pressure chamber for contact with air compressed in the combustion chamber to ignite said fuel.

3. In an internal combustion engine including a cylinder having air intake and discharge ports communicating with the cylinder thereof, a piston operable in the cylinder, a head for the engine closing the top of the cylinder, said cylinder, beneath the head constituting a combustion chamber, a relatively shallow low-pressure fuel-air chamber formed in the head immediately above the combustion chamber and substantially equal thereto in diameter and adapted for preheating and vaporizing fuel therein, a valve controlling communication between the combustion chamber and the low pressure fuel-air chamber, an intake manifold in the head above said low-pressure chamber for feeding a combustible mixture above atmospheric pressure to said low-pressure chamber, a valve between the manifold and the low-pressure chamber, said 60 valves being arranged for opposite opening and closing movement and said piston being adapted to compress air in the combustion chamber to a predetermined pressure capable of igniting the fuel-air in the low-pressure chamber upon contact therewith.

STEHMAN W. LEONARD.
